UNITED STATES PATENT OFFICE.

WALTER H. PETERS, OF STEGER, ILLINOIS.

POSTAGE-STAMP VENDING AND AFFIXING MACHINE.

1,073,515.

Specification of Letters Patent.

Patented Sept. 16, 1913.

Application filed June 14, 1911. Serial No. 633,133.

To all whom it may concern:

Be it known that I, WALTER H. PETERS, a citizen of the United States, residing at Steger, in the county of Cook and State of Illinois, have invented new and useful Improvements in Postage-Stamp Vending and Affixing Machines, of which the following is a specification.

Specifically considered the invention is primarily designed to provide a machine for vending postage stamps and affixing said stamps to letters or other matter to be sent through the mails.

A further purpose of the invention is the provision of a machine which may be used solely for the purpose of attaching postage stamps to letters or packages or which may be used for labeling newspapers, magazines and like periodicals to be sent through the mail to subscribers.

The invention supplies a feeding mechanism whereby the strip is advanced, a moistening mechanism for dampening the gummed side of the strip or the letter or package to which said strip is to be attached and a combined cutting and affixing mechanism whereby the projecting portion of the strip is severed and pressed upon the moistened part of the envelop or package placed in position to receive the same.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a view in elevation of a machine of the character and for the purposes stated embodying the invention, the coin mechanism and the rear side of the casing being removed. Fig. 2 is a view similar to Fig. 1 having parts in section and parts broken away. Fig. 3 is a horizontal section of the complete machine including the coin mechanism on the line $x-x$ of Fig. 1. Fig. 4 is a vertical transverse section on the line $y-y$ of Fig. 1. Fig. 5 is a section on the line $z-z$ of Fig. 3, looking in the direction of the arrows. Fig. 6 is a detail section of the coin mechanism on the line $6-6$ of Fig. 3. Fig. 7 is a top plan view of the front portion of the machine. Fig. 8 is a detail section on the line $8-8$ of Fig. 3.

Corresponding and like parts are referred to in the following description, and indicated in all the views of the drawings, by the same reference characters.

The machine comprises a base 1 upon which is mounted a casing 2 for inclosing the reel containing the gummed strip and the operating devices. A slot 3 is provided at the front end of the machine to receive the letters, packages or other matter to be stamped or otherwise have the gummed parts affixed thereto, such as labels. A reel 4 is rotatably mounted in the rear portion of the casing and the gummed strip 5 is wound thereon and may consist of postage stamps, labels or addresses according to the specific use for which the machine is designed. A spring 6 exerts a lateral pressure upon the reel 4 to prevent its turning too freely when the strip is drawn thereover. 75 A pair of feed rolls 7 and 8 are located in advance of the reel 4 and the stamp or other strip 5 passes between them, said rolls having their faces covered with rubber or like material to insure a positive gripping of the strip 5 which is essential to insure a proper feed thereof. A ratchet wheel 9 is attached to the feed roll 7 so as to turn therewith and two dogs 10 and 11 engage the teeth of the ratchet wheel to turn the feed roll 7 and to 85 prevent its backward rotation. The dog 11 acts as a detent to prevent backward rotation of the feed roll, whereas the dog 10 turns the feed roll to advance the strip 5.

A partition 12 is located in the front portion of the casing 2 and provides a space in which a plunger 13 is arranged to operate vertically, the stem 14 of the plunger extending through the top of the casing and terminating in a button and receiving a helical spring 15, which is of the expansible type and normally serves to hold the plunger elevated. A slot 16 is formed in the lower portion of the partition 12 for the passage of the strip 5. A guide 17 extends rearwardly 95 from the partition 12 in line with the slot 16 and consists of a flattened tube through which the strip 5 passes, said guide extending across the space formed between the partition 12 and the feed rolls and supporting the stamp strip and preventing access being had thereto from the outside of the machine through the slot 3. The lower face of the plunger 13 is covered with rubber, felt or like material to yieldingly press the postage 100 105 110

stamp or like part upon the letter or package. A plunger 18 operates in guides 19 located upon the partition 12 and extends through the top of the casing and terminates in a button and receives a helical spring 20, which normally exerts an upward pressure upon the plunger. The plunger 18 operates the feed rolls to advance the strip. A link 21 is pivotally connected at its upper end to a lug or extension of the plunger and its lower end is pivotally connected to an arm 22, which is pivotally mounted upon a journal of the feed roll 7. The feed dog 10 is mounted upon the pivot connection between the link 21 and arm 22 and is held 15 in engagement with the ratchet wheel 9 by means of a spring carried by the arm 22. When the feed plunger 18 is depressed the spring 20 is compressed and the end of the feed dog 10 is caused to ride upon a tooth of the ratchet wheel 9 and upon releasing the plunger 18 the same is moved upwardly by the spring 20 and the feed dog 10 moving upwardly with said plunger turns the feed 20 roll 9 a distance to advance an end portion of the strip 5 the proper distance, which corresponds to the length of a postage stamp when the machine is adapted for delivering such articles.

30 A blade 23 is pivotally connected to the plunger 13 and its cutting edge is pressed against the adjacent side of the partition 12 so as to sweep across the slot 16 and sever the projecting portion of the strip. The lower edge of the blade 23 is inclined to admit of the same cutting by a sheer action. A spring 24 attached to the plunger normally exerts an outward pressure upon the blade 23 to hold its lower edge in engagement 35 with the partition 12 and to throw said blade out of the way when clearing the lower end of the partition 12 so as not to interfere with the letters, packages or the like to be stamped or labeled.

40 A moistener is provided for dampening the letter, package or the like to receive the postage stamp or label. The moistener is located at the front of the casing and comprises a tank 25 and a brush 26, the latter being arranged to overhang the front portion 45 of the base 3 so that when introducing the letter, package or the like into the slot 3 it passes beneath the brush 26 and is moistened, thereby causing the postage stamp or label to adhere thereto upon operating the stamp plunger 13. The tank 25 contains a quantity of water and has a small opening in its bottom which is controlled by means of a valve 27 so that the water may drip 50 from the tank upon the brush 26 and keep the latter moist so as to dampen the letter, package or the like passing under the brush when entering the slot 3.

55 The strip 5 is gummed upon one side and 60 is wound about the reel 4, an end portion

of the strip passing between the feed rolls 7 and 8 and through the guide 17. The letters to be stamped are introduced into the slot 3 beneath the brush 26 and rest upon the front portion of the base 1. The feed 70 plunger 18 is now depressed, thereby bringing the feed dog 10 in position to turn the feed roll 11 when releasing the pressure on the plunger 18. As the plunger 18 moves upward an end portion of the strip 5 is projected through the slot 16, the portion projected being determined by the degree of movement of the feed rolls. After the feed plunger has reached the limit of its upward movement the stamp plunger 13 is 80 depressed and severs the projecting portion of the strip, which drops upon the letter and an instant thereafter the plunger comes in contact with the part of the strip thus severed and presses the same upon the letter. The strip 5 may consist of postage stamps, labels or addresses according to the particular purpose for which the machine is intended.

85 Since, as hereinbefore stated, the machine 90 is particularly designed for vending postage stamps a coin mechanism is used in connection therewith to admit of operating the feed mechanism by means of which the postage stamps are projected into proper position for delivery and attachment to the letter or other matter to be stamped. The coin mechanism is housed, being located in a casing 28 located at one side of the casing 2. The casing 28 has one or more slots 29 in 10 its top for the introduction of the predetermined coin. When the machine is adapted for delivering one cent postage stamps the casing 28 has one slot 29 only, but when the machine is designed for delivering two cent postage stamps the casing 28 has two slots 29 each adapted to receive a one cent piece. A partition 30 is located within the casing 28 and has a passage 31 therein constituting a coinway through which the coin travels 11 after being introduced into the slot 29. The coin passage 31 is enlarged at its receiving end, as indicated at 32. An arm 33 pivoted at 34 extends upwardly across the receiving end of the coin passage 31 and has a part 11 cut away at one end to form a shoulder 35 and has a portion cut away from a side to form a lateral shoulder 36, the latter forming one wall of the coin passage. A spring 37 exerts a pressure upon the arm 33 to press 12 the upper portion inward, thereby contracting the coin passage opposite the shouldered portion 36, whereby the coin is obstructed in its travel through the passage when reaching the upper portion of the shoulder 36. A vertical slot 38 is formed in the inner wall 13 of the casing 28 adjacent the casing 2 and an arm 39 projecting laterally from the feed plunger 18 is arranged to operate in the slot 38. The shouldered portion 35 of the arm

33 extends across the slot 38 and limits the downward movement of the arm 39 and the feed plunger, thereby preventing operation of the feed mechanism.

5 When a coin is introduced into the slot 29 it passes by the arm 39 and lodges in the contracted portion of the coinway opposite the shoulder 36 formed on the arm 33. Upon depressing the feed plunger 18 the 10 arm 39 is carried downward and engaging the coin forces it through the contracted portion of the coinway, with the result that the upper portion of the arm 33 is moved to one side to withdraw the shoulder 35 out 15 of the path of the arm 39, thereby admitting of the plunger 18 descending to the limit of its movement, which is essential to insure proper feed of the strip 5. As the pressure is removed from the plunger 18 it rises and 20 at the same time turns the feed rolls 7 and 8 and when the plunger reaches the limit of its upward movement the upper portion of the arm 33 is returned to normal position by the action of the spring 37 to prevent 25 downward movement of the plunger 18 until after another coin has been placed in position. When the machine is adapted for delivering two cent postage stamps it is to be understood that two arms 33 and adjunctive 30 parts are provided and it is necessary to place a one cent piece in each slot 29 so that when depressing the plunger 18 both arms 33 are operated to withdraw their shoul- 35 dered portions 35 from the path of the arm 39.

From the foregoing description, taken in connection with the accompanying drawings, the advantages of the construction and of the method of operation will be readily 40 apparent to those skilled in the art to which the invention appertains, and while I have described the principle of operation of the invention, together with the device which I now consider to be the embodiment thereof, 45 I desire to have it understood that the device shown is merely illustrative, and that such changes may be made when desired as are within the scope of the claims appended hereto.

Having thus described the invention what 50 is claimed as new, is:—

1. In a machine of the character described, the combination of a plunger, a mechanism adapted to be operated by means of the plunger for effecting delivery of the 55 article, a part having a coinway, an arm having an end portion cut away on one side and at one edge to provide a side and an edge shoulder, the reduced part of the arm extending into said coinway and arranged 60 at one side thereof with the side shoulder at one edge of the coinway to reduce the width thereof, and a part projecting from the plunger across said coinway and limited in its movement by the edge shoulder of the 65 arm and adapted to engage a coin to push the said arm aside to cause the before mentioned side shoulder to clear the coin to admit of full operation of the plunger to effect 70 delivery of the article.

2. In a machine of the character described, the combination of a plunger for operating a delivery mechanism having a laterally extending projection, a part having a coinway which is enlarged at its receiving end, and a slot intersecting the coinway and receiving the projection of the plunger, and a pivoted arm having an end portion reduced and arranged at one side of the coinway and forming part of the wall 80 thereof, said reduced part of the arm having an edge shoulder to limit the movement of the plunger by engaging the projection thereof, and a side shoulder to contract the width of the coinway to arrest the movement 85 of the coin, the parts being arranged to admit of the projection of the plunger engaging a coin to move the edge shoulder out of the path of the plunger projection, whereby full 90 operation of the delivery mechanism may be attained.

In testimony whereof I affix my signature in presence of two witnesses.

WALTER H. PETERS.
